UNITED STATES PATENT OFFICE

159,215

ELECTRIC HEAT-TREATING FURNACE

Harold E. Koch, Pewaukee, Wis., assignor to Hevi
Duty Electric Company, Milwaukee, Wis., a cor-
poration of Wisconsin

Application April 27, 1949, Serial No. 2,296

Term of patent 14 years

(Cl. D26—5)

To all whom it may concern:

Be it known that I, Harold E. Koch, a citizen of the United States, residing at Pewaukee, in the county of Waukesha and State of Wisconsin, have invented a new, original, and ornamental Design for an Electric Heat-Treating Furnace, of which the following is a specification, reference being had to the accompanying drawings, forming part thereof.

Fig. 1 is a front perspective view of an electric heat treating furnace showing my new design;

Fig. 2 is a rear perspective view thereof; and

Fig. 3 is a view similar to Fig. 1 with the furnace open.

I claim:

The ornamental design for an electric heat-treating furnace, as shown.

HAROLD E. KOCH.
